Des. No 6

John Good, Philadelphia Pa.
Letters Patent No. 6, dated August 17th, 1843.

The Schedule referred to in these Letters Patent and making part
of the same.

To all whom it may concern: Be it known that I,
John Good, of Philadelphia in the State of Pennsylvania,
have invented a new design of an apparatus which I de-
nominate a Corpse Preserver; which apparatus, although
there is not anything new in the principle of its action, is
new in its shape and configuration, and neat in its appear-
ance. Its intention is to preserve the bodies of the dead in
warm weather, during the period which elapses between the
time of decease and interment.

2

It is the usual practice when the preservation is to be effected by ice, to place it upon, and make it surround the corpse; a plan which is not only very troublesome and uncleanly, but is calculated to harass the feelings of surviving friends, at a time when everything should be sought that is soothing.

In the accompanying drawing fig. 1. represents the apparatus ^{impart} which I have designed for this purpose. A, A, is an outer case, made somewhat in the form of a coffin, and B, B', a close-fitting lid which is furnished with a glazed opening at B', through which the face of the deceased may be seen. Fig. 2, is a top view of the case A, A, the lid, B, being removed; the case is made double, there being a partition C, C, which reaches from the bottom of A, A, to within four or five inches, more or less, of its top, leaving a space D, D, of several inches between the two, which is to be filled with ice. E, E, fig. 3, represents a false bottom, which is shown as perforated with numerous holes; this, however, is not absolutely necessary. This false bottom fits within the partition C, C, and rests upon ledges which keep it some four or five inches above the bottom of the case A, leaving a space which is also a receptacle for ice. The corpse is to be deposited on this false bottom. E', E', is an edge view of it. F, F', is a tray, which is shown edge wise at F, "F," in a vertical section along its middle; this tray drops into the case A, A, below its lid B, B'; it is glazed at F' in an opening corresponding with that of B' in the lid. The part F' is furnished with a flaunch, as shown at G, G, to retain the ice. This tray is four or five inches deep, and is to be filled with ice.

Fig. 5, is a longitudinal vertical section through the apparatus, the false bottom and tray being within the case A, A. In this figure, the respective parts are marked with the same letters of reference as in the others. H, H, are openings through the lower part of the partition C, C, to allow the water from the melting ice to pass into the glacia-

11.

below the false bottom, in order that the whole may be carried off by the waste pipe a.a.; that from the tray, escapes through the pipe b.b.

This apparatus may be best made of tin plate, but it may be formed of other metal, of wood or of any other suitable material.

Having thus, fully described the manner in which I form my apparatus, and having, in the accompanying drawing, shewn the design thereof, I hereby claim as new, and desire to secure by Letters Patent, a Corpse Preserver, the shape and configuration of which is substantially such as I have herein made known and represented in the drawings thereof.
